J. GEORGE JUNG, OF NEWARK, NEW JERSEY.

Letters Patent No. 84,359, dated November 24, 1868.

IMPROVED METHOD OF CONSTRUCTING CHAINS.

The Schedule referred to in these Letters Patent and making part of the same.

Be it known that I, J. GEORGE JUNG, of Newark, Essex county, State of New Jersey, have invented a chain, as a new article of manufacture in jewelry, and which I denominate "The Fish-Scale Chain," and I hereby declare the following to be a clear and full description thereof, reference being had to the annexed drawings, of which—

Figure 1 is a perspective view of a link as it appears when cut out of sheet-metal, and before being bent;

Figure 2, a perspective view of the link after being bent, and before being connected with others;

Figure 3 represents a front view of the chain, showing the flat side of the said chain; and

Figure 4, a sectional view.

This fish-scale chain is constructed in the following manner:

The links are made of sheet-metal, and stamped out in the usual manner by punches and dies, and their outline shape or configuration is immaterial; but there must be a head, *a*, at each of the two extremities of the link, and the necks *b*, connecting these two heads *a a* with the body of the link, are narrower than the heads; and there must be two apertures in the body of the link, at equal distances from the heads *a a*, and

on a straight line drawn through the centres of the said heads, which apertures must be wide enough to admit the passage of the heads of the succeeding link.

In order to form these links into a chain, the links are first bent up, as shown in fig. 2, and the heads *a a* of each link are introduced into the apertures *c c* of the succeeding link, and then turned down, as clearly shown in fig. 4. The neck *b* being narrower than the aperture, gives to the links sufficient freedom of motion, and thus the chain so formed is a very pliable one.

The chain can also be manufactured by very simple machinery.

Having now fully described my invention,

What I claim therein as new, and desire to secure by Letters Patent, is—

As a new article of manufacture, a chain, constructed of links having two heads and two apertures, in the above-described location to each other, and the links being interlinked, substantially as specified.

J. GEORGE JUNG.
